(57) **CLAIM**

The ornamental design for an anchor joist for architectural structures as shown and described.

DESCRIPTION

FIG. 1 is an isometric front top view of a design for an anchor joist for architectural structures.

FIG. 2 is a left-side elevational view of the design for the anchor joist for architectural structures.

FIG. 3 is a right-side elevational view of the design for the anchor joist for architectural structures.

FIG. 4 is a top plan view of the design for the anchor joist for architectural structures.

FIG. 5 is a bottom view of the design for the anchor joist for architectural structures.

FIG. 6 is front elevational view of the design for the anchor joist for architectural structures.

FIG. 7 is a rear elevational view of the design for the anchor joist for architectural structures; and,

FIG. 8 is an enlarged front elevational view of the design for the anchor joist for architectural structures.

The anchor joist for architectural structures is shown with symbolic breaks in its length in denoted by broken lines. The jagged break lines, and the appearance of any portion of the

(Continued)

anchor joist for architectural structures between the jagged break lines form no part of the claimed design.
